GARMENT HANGER

Helen E. Douglas, 610 N. Spark St., Burbank, Calif.

Filed Apr. 26, 1965, Ser. No. 84,946

Term of patent 14 years

(Cl. D80—8)

FIG. 1

FIG. 2

FIG. 1 is a side elevational view of a garment hanger, showing my new design;

FIG. 2 is a bottom view of the garment hanger, as illustrated in FIG. 1;

FIG. 3 is a left hand end view of the garment hanger, as illustrated in FIG. 1;

FIG. 4 is a top plan view of the garment hanger, as illustrated in FIG. 1, and

FIG. 5 is a side elevational view of the garment hanger of FIG. 1 with both garment arms shown in an extended position.

The end view opposite the end view shown in FIG. 3 or the right hand end view, not shown, is substantially identical to the end view illustrated in FIG. 3.

I claim:

The ornamental design for a garment hanger, as shown and described.
